UNITED STATES PATENT OFFICE.

FRANCIS HICKMAN, OF NEW YORK, N. Y.

DESIGN FOR A GAS-FIXTURE.

SPECIFICATION forming part of Design No. 17,078, dated February 1, 1887.

Application filed December 6, 1886. Serial No. 220,864. Term of patent 3½ years.

To all whom it may concern:

Be it known that I, FRANCIS HICKMAN, a citizen of the United States, residing at New York, in the county of New York and State of 5 New York, have invented and produced a new and original Design for Gas-Fixture Distributors, of which the following is a specification, reference being had therein to the accompanying drawings.

10 Figure 1 is a side elevation of a portion of a drop-light, showing my newly-designed distributor and its pillars; and Fig. 2, a plan view of the distributor with its pillars.

The feature of my design consists in making 15 the distributor of substantially the form of a frustum of a pyramid, whereby a plurality of surfaces from the bottom toward the center is produced. The distributor is shown on a drop-light or other gas-fixture tube, B, and is preferably formed with a short collar, C. The bot-

tom of the distributor may or may not be provided with an ornamental termination, as seen at D. At one or more points pillars E, having tips F, are provided.

Having thus fully described my invention, 25 what I claim as new, and desire to secure by Letters Patent, is—

A design for a gas-fixture distributor, consisting of a body having a plurality of exterior flat surfaces inclined inwardly toward the 30 upper end and outward toward the lower end, and forming a frustum of a pyramid, as shown, and having one or more pillars projecting from said flat surfaces, as shown.

In testimony whereof I affix my signature in 35 presence of two witnesses.

FRANCIS HICKMAN.
